U.S. Cl. D48—24 A

FIG1

FIG4

FIG2

FIG3

FIG5

FIG. 1 is a perspective view of a flashlight showing my new design;

FIG. 2 is a top plan view thereof;

FIG. 3 is a bottom plan view thereof;

FIG. 4 is a front elevational view thereof; and

FIG. 5 is a rear elevational view thereof.

The right side of the design has the same appearance as the left side illustrated in FIG. 1.

I claim:

The ornamental design for a flashlight, as shown and described.
